UNITED STATES PATENT OFFICE.

JOHN C. LESHER, OF SAN FRANCISCO, CALIFORNIA.

MINERAL-SEPARATOR.

1,281,596.

Specification of Letters Patent. Patented Oct. 15, 1918.

Application filed July 26, 1917. Serial No. 182,889.

To all whom it may concern:

Be it known that I, JOHN C. LESHER, a citizen of the United States, residing at the city and county of San Francisco and State 5 of California, have invented certain new and useful Improvements in Mineral-Separators, of which the following is a specification.

My invention relates to that class of devices for separating minerals, particularly precious metals, from accompanying substances, in which a flowing stream of the material is passed through a shaking sluice box and is subjected to impediments, screening agencies and retaining devices therein, whereby the separation is effected.

While my invention is applicable to any form of structure or machine by which the material is obtained, prepared and delivered 20 to the separator, it is particularly intended for use, and is effective in that type of mineral saving machines commonly known as dredgers, and in which a digging elevator excavates and lifts the material to a screen, 25 usually in the form of a rotating sifter known as a grizzly, which preliminary divests the material of its coarse components such as rocks, etc., and delivers the remainder to the value saving devices.

I shall, therefore, illustrate my invention in connection with a dredging machine of this type.

The object of my invention is to effect a thorough separation of the precious particles from the gangue, and to this end my invention consists in the novel separator which I shall hereinafter fully describe, by reference to the accompanying drawings, in which—

Figure 1 is a side elevation of a dredger including my separator with parts broken away.

Fig. 2 is a top plan view of the separator partly in section, on the line 2—2 of Fig. 3.

Fig. 3 is a side elevation of the same partly in section on the line 3—3 of Fig. 2.

Fig. 4 is a cross section on the line 4—4 of Fig. 2.

Referring to Fig. 1, the numeral 1 is a foundation, supporting the general frame 2.

At one end of the frame is pivotally mounted at 3, the elevator 4, comprising the endless traveling chain of digging and elevating buckets 5. The angle of the elevator

is regulated by a line 6, directed to a winch 55 7. The endless chain of buckets 5 is driven by a belt 8 from a shaft 9 to which power is led by a belt 10 from a drive shaft 11.

In the frame 2 is mounted the rotatable preliminary screening device or grizzly, 60 comprising an inner member 12 of a grating type, indicated by the dotted lines, and an outer member or cylinder 13. This device is rotated by a gear 14 on its end, with which meshes a pinion 15 on a shaft 16 driven by 65 a belt 17 from the shaft 9.

The grizzly device is inclined and is mounted for rotation on rolls 18 by means of tracks 19. The elevator 5 delivers the excavated material to the inner grated member 12 of the grizzly, through a chute 20. The inner member 12 delivers to a discharge chute 21. The outer member or cylinder 13 delivers into the head end of the inclined upper sluice box 22, the foot of said box delivering into the head end of the lower inclined sluice box 23. Each of these sluice boxes is suspended at its foot end by links 24, and each is given a combined longitudinal and vertical shake or movement by 70 means of an arm 25 secured to its head end, said arm being secured to an eccentric 26. The eccentric of the upper box is driven by a belt 27 from the shaft 9, and the lower eccentric is driven by a belt 28 from the shaft 85 of the upper eccentric.

29 is a pump, with suction 30. The pump delivers water through the pipe 31 into the grizzly.

The operation of the machine in general is 90 as follows:—The material excavated by the digging buckets 5 is elevated and delivered through the chute 20 into the grizzly, in which the coarse material, rocks, etc., are separated and delivered by the inner member 12 to the discharge chute and deposited on the dump. The remaining portion of the material is delivered from the outer member 13 of the grizzly into the first sluice box 22. In this box the values are separated 95 and may be recovered from a drawer 22' of said box or other clean up device. Such of the values as are not saved in the first sluice box, are saved in the second box 23 and recovered from a drawer 23' or other clean up 100 device.

Now, referring particularly to Figs. 2, 3 and 4, the details of the sluice boxes may

be specifically described. Both boxes are alike, and the description of one will apply to the other.

In the bottom of the sluice box 22 is a 5 layer 32 of material adapted to catch and retain the fine concentrates. Cocoa-matting is usually employed and is found effective, though other material or fabric, such as carpet and the like, may be used.

10 In the box 22 is fitted a shell comprising side walls 33, and longitudinal foot members 34, the side members being secured to the walls and the middle member secured by straps 35 to the side members, as shown in Fig. 4. Upon these foot members lies a 15 screen 36. To the side walls 33 of the shell are secured the baffle plates 37. These lie above the screen 36 and are secured at each end to the side walls 33 by the angles 38 20 as shown in Fig. 2.

The baffle plates 37 traverse the shell at an angle, successive plates being at opposite angles, as seen clearly in Fig. 2.

Each baffle plate is notched upwardly 25 from its lower edge, forming a plurality of openings 39 in each. The openings of successive plates are staggered, that is to say, the openings in one plate are out of line with those of adjacent plates, as seen in 30 Fig. 2.

The effects of this construction may be described as follows:—In general, these are a prolonged course for the stream of material, increased rapidity of flow due not only to the inclination of the box, but also to the alternate angular disposition of the baffle plates, tending to a continuous gravity effect, and an agitation of the stream, due to the shake of the box, the rapidity of and 40 the obstructions to the flow, and the staggering relation of the openings in the baffle plates. These all tend to a separation of the heavier and precious particles from the lighter and worthless particles, which latter are held in suspension in the stream and are carried off, while the values pass through 45 the screen and are caught in the fabric mat below.

The stream of material entering at the 50 head of the box, encounters first the leading baffle plate, and is broken up with a tendency to distribution in passing through the openings in this plate. This distribution is, however, not an equal one, for the angular disposition of the plate induces a stronger flow to one side, and this is repeated to the other side by the second plate, and so on from side to side, the sum of said flows, however, resulting in an average equal distribution for the whole process. Thus the 55 stream is positively kept on the move to the greatest extent, is agitated throughout,

broken up, reunited, impeded and so affected in general as to result in an assured separation of the values.

65

In a machine of the dredger type, sluice boxes, such as I have described, have a peculiar value, in that in such machines the preliminary preparation of the material to be separated and its precious particles removed is necessarily rather crude and incomplete, as the elevator excavates and supplies the material in the rough and the grizzly merely separates the very coarse components, leaving the remainder in a condition requiring rather strenuous treatment to insure effective separation of its values. The peculiar movement of the sluice box, due to its freely swinging suspension at one end and the directly connected eccentric arm at the other end, gives a swirling motion to the stream between the baffle plates, as is indicated by the arrow in Fig. 3, which motion is also effective in the general agitation of the stream.

75

70 I claim:—

1. A separator comprising a sluice-box; a value retaining fabric in the bottom of the box; a screen spaced above said fabric; and a plurality of spaced baffle plates above the screen, extending from side to side of the box and diagonally disposed successively at opposite angles, each plate having a plurality of openings in its lower portion.

80

2. A separator comprising a sluice-box; a value retaining fabric in the bottom of the box; a screen spaced above said fabric; and a plurality of spaced baffle plates above the screen, extending from side to side of the box and diagonally disposed successively at 90 opposite angles, each plate having a plurality of openings in its lower portion, said openings in successive plates being out of line with the openings of the previous plate.

95

3. A separator comprising an inclined sluice-box; means freely suspending said box at one end, an eccentric-driven arm secured to the other end of the box; a value retaining fabric in the bottom of the box; a screen spaced above said fabric; and a plurality of spaced baffle plates above the screen extending from side to side of the box and diagonally disposed successively at opposite angles, each plate having a plurality of openings in its lower portion relatively staggered in successive plates.

100

110 In testimony whereof I have signed my name to this specification in the presence of two subscribing witnesses.
